UNITED STATES PATENT OFFICE

MARC STERN, OF FLINT, MICHIGAN, ASSIGNOR TO A C SPARK PLUG COMPANY, OF FLINT, MICHIGAN

DIE-CASTING MACHINE

Application filed June 4, 1926. Serial No. 113,707.

- This invention relates to the problem of making castings. It aims to provide an improved die casting machine. The machine has been designed particularly for making 5 speedometer parts, but it will be understood that dies or molds for all sorts of castings may be substituted for that shown in this application, and that the usefulness of the machine is very extensive.
- 10 It is an object of the invention to make a machine of the kind indicated, which is automatic in its action. It may be continuously automatic, or automatic for a single cycle of operations only.
- 15 It aims to employ a die or mold of two sections, one of which is a stationary rear section, the other is a forward movable section. This is for the purpose of rigidity and perfection of alinement.
- 20 A further object is the removability of a melting pot and a furnace therefor as a unit. As another object the invention provides automatically removable cores and in this connection employs means to remove a core 25 or cores from the front movable die member, as well as from the fixed or ejector part of the die.
- The invention has for a further object to provide means to wipe off from the nozzle 30 and the adjoining die opening any metal which may stick to these parts after the die has been charged with molten metal.
- A further object to be attained is the provision of means to extract the cores, not 35 only in the cover half of the die but also from the fixed or ejector portion and to draw these cores out in any direction necessary.
- The adaptability of the machine for a wide 40 variety of uses will be understood from the above brief statement of the objects of the invention. To these objects others might be added. These need not be enumerated, however, as they will be obvious upon reading the appended specification.
- 45 The specification is to be read together with the drawing, which is to be understood as illustrative only, as modifications may be made to produce other castings in which the shape of the casting differs and in which 50 different cores may be required.

In the drawing:

Figure 1 is a plan view of the machine, certain parts being shown in section to better illustrate the structure.

Figure 2 is a side elevation.

55

Figure 3 is a front elevation.

Figure 4 is a rear elevation.

Figure 5 shows in transverse elevation the means for wiping the metal from the nozzle.

Figure 6 is an elevation at right angles 60 to Figure 5, showing the same parts.

Figure 7 is a transverse section through the clutch.

Figure 8 is a transverse section taken between the parts of the mold.

65

Figure 9 is a longitudinal sectional view of the melting pot.

Referring to the drawing by reference characters, numeral 1 represents the frame or bed of the machine. To each side of frame 70 1 at the front of the machine are secured for vertical adjustment by screw members 2 knee members 3.

Upon these knee members is slidably mounted a platform 5. Secured to the platform 5 by bolts 6 is a melting pot 7. Enclosing the melting pot is a furnace 35. Lugs 38 extending from furnace slidably engage bolts 40 depending from the platform, there preferably being at least three of such bolts, 80 as shown. Upon each bolt are a pair of springs 37, one on each side of lug 38. By this method of mounting the furnace from the platform, a resilient support is obtained so that the shocks of the reciprocating platform are absorbed, in part, before reaching the furnace.

Projecting upwardly from the platform on each side thereof is a cross head guide 9. Slidable on the guides is a cross head 11 90 into which is detachably engaged the enlarged end of a plunger rod 13. The latter extends into a cylinder 15 within the melting pot, which cylinder communicates with the melting pot by means of openings 17 95 within the wall of the cylinder at a point below the upper extremity of the plunger movement. One of such openings is shown in the sectional view, Figure 9. For reciprocating the plunger cross head, the latter is 100

secured to an upwardly extending rod 19 attached to the lower end of a piston rod 21 by means of a pin 23 passing through an opening in the rod 21 and through openings 5 in the sides of an open cylindrical extension 25 of rod 19, as best shown in Figure 3. The upper end of rod 21 carries a piston 27 within a cylinder 29. Into the latter, on each side of the piston, compressed air may be 10 admitted by flexible pipes 31. These flexible pipes communicate with the valve 33 which is actuated in timed relation to the other operative parts in a way to be explained. The fuel for the furnace will also 15 be supplied by flexible members connecting at the bottom of the furnace as shown at 39 in Figure 2.

The cylinder 15 communicates with the nozzle 41 of spherical shape by means of a 20 passage 43. The opening from the nozzle 41 into the die is shown by dotted lines in Figure 9. Figure 9 also shows the two parts of the die, a front section 44, which is movable and a rear portion 45, which is fixed. At 25 42 is shown a water pipe intended to show that the die may be water cooled by appropriate passages if desired. In the course of the operation molten metal is apt to stick to the nozzle of the melting pot and to the 30 mouth of the die. For that purpose it is desirable to provide means for automatically wiping off such molten metal as may collect on these surfaces. It should be stated that during the operation of the parts, as 35 will be explained below, the nozzle is moved away from the die. For the purpose of wiping off the metal the structure shown in Figures 5 and 6 has been devised.

An angular longitudinally positioned slot 40 48 is provided in the bed frame. The movable platform in the vicinity of the nozzle carries a reciprocally mounted rod 47, the lower end of which carries an anti-friction roller 49 movable in the slot 48. As the platform reciprocates the roller moves up and down in the angular part of the slot, as 45 shown in Figure 6. It thereby swings a bell crank 51 pivoted at 53. The bell crank shaft carries an arm 54 with a wiper 56, which 50 moves over the discharge opening as shown by dotted lines in Figure 5.

For producing the movements of the several parts in proper timed relation power is taken from an external source as from the 55 motor, not shown, by means of a belt 57 (Figure 1) to a pulley 59 rotatably mounted on the shaft 61. The pulley carries a driving cone member 63 of a clutch, see Figure 7. The driven clutch member 65 is slidably, but not rotatably, carried on shaft 61, a key 67 affording the sliding relation. The clutch member 65 is surrounded by a rotatable sleeve 68, which has projections or pins 70 extending into an annular groove in the hub of the clutch member to hold the mem-

ber and sleeve against relative axial movement, and which sleeve also carries a pin 69, (see Figure 4) movable in a cam slot 71 of a fixed housing member 73. For manually operating the clutch, a reciprocable member 75 is moved by a lever 77 and a connecting link 79. The member 75 has a plurality of teeth 80 to engage corresponding teeth on sleeve 68, whereby movement of the lever 77 gives a rotary movement to the sleeve 68, which rotary movement is converted by the pin and slot connection into a reciprocating movement such as to effect clutch engagement for the purpose of driving shaft 61.

The shaft 61 carries at its other end a pinion 81 in driving engagement with a gear 83. This gear is mounted on a shaft 85, and a pinion 87 on the end of the shaft 85, drives a gear shaft 89 by engagement with gear 91. Also carried on shaft 89 is a pinion 93 which drives a large gear 95 mounted on a transverse shaft 97. Also secured to said transverse shaft 97 are driven members 99 and 101. Three members 95, 99 and 101 serve to operate the several parts of the machine, as 90 will be explained.

On the near face of gear 95 (facing the machine as in Figure 2) is a cam slot in which is movable an anti-friction roller 96. This roller is carried by a lever 103. This lever 103 is pivoted to the base at 105 and at its upper end is pivoted to a link 107. The forwardly extending link 107 is pivoted to a cross bar 109 carried on the ends of pivoted arms 111. Extending forwardly from the 100 ends of cross bar 109 are links 113 which are connected to the movable platform, as perhaps best shown in Figure 2. Operatively associated with the pivoted ends of lever 103 and link 107 is a rubber block 106. When 105 the movable member is moved so that the nozzle is moved to its active position the rubber cushion 106 insures a tight fit between the melting pot and the die members and compensates for any variation in the expansion of the hot members which are to be locked together. While the yielding means may be something other than a rubber block, the rubber block is preferred because of its greater dependability.

In a cam slot on the other side of gear 95 is a roller 115 connected to a dove tail slideable member 117. This member reciprocates a cross head 119 from the ends of which extends rods 121 passing through guides 123 and carrying the forward half of the die for the casting.

The lever 125, Figure 2, is rotated about its pivot 127 by a roller 100, at its upper end moving in a cam slot in member 99. By means of link 129 connected to the lower end of lever 125 a bell crank 131 is rotated to impart vertical reciprocation to a rod 133. This rod is connected to the end of a cross bar 135. The other end of the cross bar may be connect- 130

ed to a similar vertical rod pivoted to a rocking member on the other side corresponding to a bell crank 131, this being for the purpose of proper control of the cross bar 135. 5 The bar 135 is intended to raise a core 139 from the front or movable die member. To raise a vertical core 141 from a position partly in the fixed and partly in the movable die member is shown a bell crank 143 operated by 10 a link 145. The roller 137 travels in a cam slot in driven member 101 to swing lever 136. This lever is almost directly behind lever 125 but may be seen by the dotted lines in Figure 2. The lever is connected by a link 138 with 15 the rock arm 147. This rock arm rocks the shaft 146. From shaft 146 upwardly projecting arms 148 carry the head 149. Projecting upwardly from head 149 is an arm 151. This arm is connected at its upper end to link 20 145, which has been referred to as the operating means for the bell crank 143. The head 149 also has a depending arm 153, shown in dotted lines in Figure 2. From the lower end of arm 153 a link 155 extends forward to actuate a core which enters horizontally into the die. The action may be effected by crank 150 connecting the forward end of rod 155 to a vertical shaft 152. This shaft may horizontally reciprocate the core member by means of 25 30 a pinion and rack. Figure 8 is intended to show this construction part 156 representing the horizontal core member and 154 the pinion on the vertical shaft.

Movable with the cross head 149 is a sliding member 158 which guides by means of the passage therethrough a rack member associated with a plunger and ejecting pins to be described below.

In Figure 4 will be seen a shaft 157 with 40 a crank 159, the roller at the end of which moves in a cam slot 161 on the peripheral face of member 101. The consequent periodical rotary movements of shaft 157 are transferred to shaft 163 by means of a sprocket and chain connection at 165, as shown. The periodical rotary movements of shaft 163 actuates the valve 33 for determining the reciprocation of the plunger in the cylinder of molten metal, as explained above.

50 At 167 is seen another roller engaging the cam slot in the further side of member 101. This roller 167 effects a reciprocation of a rod 169, in much the same way that roller 115 actuates the rod 117. The last named rod, by 55 means of a crank 171, rocks the shaft 173 carrying a pinion 174 engaging the rack 176, mentioned above. As explained above, this rack has a sliding engagement in the member 158 which moves with the cross head 149. 60 It will be understood that the member 158 is cut away to provide for the rack and pinion engagement, as described. The movement of the rack effects the movement of the plunger 175 connected therewith. The plunger 175 carries pins 177 which move to eject the cast-

ing from the mold, after the separation of the halves of the mold.

Carried on the end of the main shaft (Figure 1 and Figure 2) is an arm 181 to which is pivotally connected a rod 183. The rod 183 is guided between upwardly connected lugs 185 of a frame bracket. Rod 183 has a roller 187 which is arranged to travel on a horizontal part 189 of the bracket. The rod 183 has a notch 191 for engagement with a lug 192 on the driven clutch member 65 during its reciprocating movements. The arrangement is such that the clockwise reciprocation of the main shaft shall, during the forward movement of the rod 183, engage the driven clutch and by its rotary and reciprocatory movement due to the pin and cam slot effect a clutch release after the mechanism has formed the casting and opened the die. After the clutch is released the roller 187 rides horizontally on the bracket 185 and lifts the rod from the clutch and the mechanism is out of operation until a subsequent manual operation of the lever 77. It should be noticed that the ordinary clutch release mechanism in the clutch releasing action also moves the rack 75 back to its starting position, so that when the operator again wishes to start the mechanism, the lever 77 may be swung forward to start the machine. It will also be noticed that if the rod 183 is removed from the machine, or, if it is swung back out of operating condition, the machine will continue to function automatically to make castings, one after another. When the rod 183 is in operation, the automatic action is for a single cycle of operations only, after each of which the operator will again put the parts into operation by movement of the lever 77.

The operation may be briefly described as 105 follows: Assuming that the furnace is in position and that the melting pot is supplied with molten metal, and that the die members are separated and the cores removed, the operator swings the lever 77 to the right, to the 110 position shown in Figure 2. This slides the driven clutch member 65 into engagement with the driving clutch member 63. The gear train thereupon rotates the driving means 95, 99 and 101, on shaft 97. By means of the mechanism described, the front die section is drawn back into alignment with the fixed rear part; the several core members are inserted into the die; the platform with the melting pot is pulled back to bring the nozzle into engagement with the mouth of the die; and the compressed air valve is actuated to move the plunger and force a charge of molten fluid into the die. The casting is thus formed and at once is cooled, water 115 cooling being made use of, if desired.

Thereupon, a continuation of the rotation of the driven members removes the cores from the die, raises the plunger to admit a new charge into the cylinder, moves the plat-

form forward, the metal sticking to the nozzle and the mouth of the die is wiped off and the forward die section moves away from the rear portion. The ejector pins on the plunger then push the casting from the die. If now the rod 183 is not in use, the cycle of operations is repeated and continues until the lever 77 reverses the motion of the driven clutch member 65 and stops the machine. If, 10 however, the rod 183 is in position, as shown in Figure 2, as the cycle of operations becomes complete, the rod 183 de-clutches the machine from the driving means and, in order to again throw it into operation, the operator 15 must swing lever 77.

The several instrumentalities are all thus operated in proper timed relation and the machine may be operated continuously or by the use of rod 183 may automatically stop 20 after each cycle of operations.

The detachable parts at 23 and 25 afford a convenient means of separating the cylinder 29 and related parts from the melting pot. A convenient manipulation may be had by forcing down piston 27, disconnecting 23 from 25 and thereafter raising the piston 27 leaving the cross head down. The cross head may then be lifted in separating it from part 13.

I claim:

30 1. In a die casting machine, a pair of co-operating die members, means to stationarily mount one of the die members on the machine, actuating mechanism for moving the other die member relative to said stationary die member, to open and close the die cavity, said movable die member having a sprue opening leading to the die cavity from a point spaced from the parting surfaces of the die members, whereby cores can be pulled in any direction 40 at right angles to the axis of said sprue opening, a movable furnace-melting pot unit having a discharge nozzle engageable with said sprue opening, means to move said unit to bring the nozzle into engagement with the sprue opening when the die members are 45 closed, cores carried by both the stationary and the movable die sections, projectable into the die cavity, and automatic actuating means for retracting the cores in timed relation with 50 the parting of the die members.

55 2. A die-casting machine including a die formed in separable sections, one of which is provided with a sprue opening disposed at an angle to the parting line of the die sections, a furnace and pot unit movable relative to said sections to bring the nozzle of the pot into communication with the sprue opening, a driven member, mechanical connections between the member and the die and the furnace pot unit respectively, for their actuation in pre-determined relation through a series of cycles for making castings.

60 3. In addition to the elements of claim 2, means for rendering the mechanism continuously operative and other means operable

in a pre-determined position to limit the operation to a single cycle of movements.

4. A die casting machine having a stationary main frame, and an ejector die portion fixedly mounted on the frame and a movable portion, ejecting pins associated with said stationary portion, means for actuating said pins, and means whereby the movable portion is automatically moved to and from a position for completing the die. 70

5. In a die casting machine, a die comprising separable sections and a melting pot and movable furnace adjacent thereto, automatically operated means for moving the melting pot and furnace to and from the die in a direction at right angles to the parting line 80 of the die sections.

6. In a die casting machine a die, a supporting platform, a melting pot and a furnace both supported by said platform, automatically operated, means for moving the platform to carry the melting pot and the furnace to and from the die in a direction angularly to the plane of the parting surfaces thereof. 85

7. In a die casting machine, a frame, a die, a melting pot movable on said frame into and out of contact with said die, a wiper movable over the nozzle of the pot and the mouth of the die to wipe the same, and operating means for the wiper automatically actuated by the relative movement of the frame and melting pot. 90

8. In a die casting machine, a pair of die members including a stationary member, a movable member, power driven means to actuate said movable member, a core insertible wholly within said movable member, a second core insertible partly within each member, means operating automatically to remove said cores in timed relation, an ejector pin associated with the stationary member, and automatically actuating means therefor. 100

9. In a die casting machine, a stationary main frame, a fixed die member mounted on the frame, a die member movable relative thereto, an ejector for forcing the casting from the fixed die member, means automatically operable to open the die and eject the casting. 110

10. In a die casting machine including a pair of die members, one of which is a fixed ejector part and the other a movable cover part, a clutch, manually operable means for actuating the clutch, a driven shaft, means operable by a single rotary movement of the said shaft to assemble the die, insert the cores, force the metal into the die, restore the parts to initial position and thereafter eject the casting, and, automatically operable means for releasing the clutch after said single series of operations. 115

11. In a die casting machine, an ejector die and a cover die, the former being fixedly mounted on the machine and the latter being 120

125

movable to and from a position closing the die cavity, an ejector pin associated with the ejector die and movable into and out of the die cavity, and actuating means therefor to move the ejector pin in timed relation with the movement of the cover die.

12. The invention defined by claim 11, together with cores movable into and out of said die members, power driven means to pull the cores from the cover die, separate the cover die from the fixed ejector die, thereafter pull the cores from the fixed ejector die, ejector pins movable through the ejector die, power driven means to move said pins to eject the casting as the last step in the sequence of operations.

13. A die casting machine including die members movable relative to each other in a horizontal plane, and a furnace movable relative to said die members also in a horizontal plane and as a part of the operating cycle of the machine.

14. A die casting machine including relatively movable die members, a furnace and a melting pot associated with the furnace, said furnace being movable relative to and in the same direction as said die members to bring the melting pot into communication with the die cavity as a part of the operating cycle of the machine.

15. A die casting machine including a pair of die members, means to open and close said die members, a furnace, a melting pot carried by the furnace, and means to move said furnace relative to said die members and at an angle to the parting line thereof to bring the pot into communication with the die cavity through a sprue opening in one of the members that extends angularly to the parting line each time the die members are closed.

16. A die casting machine including a pair of die members, one of which is movable, a furnace and a melting pot carried by the furnace, said furnace and melting pot being movable as a unit relative to said die members in a direction angular to the plane of the parting surfaces when the die members are closed.

17. A die casting machine including a pair of relatively movable die members, a furnace movable relative to said die members as a part of the operating cycle of the machine and a melting pot fixedly mounted on the furnace for movement therewith and having communication with the die cavity at one limit of relative movement, through a sprue opening that extends through one of the die members at an angle to the parting line, said furnace and pot being removable as a unit from the machine.

18. A die casting machine, including a pair of relatively movable die members, a melting pot furnace, and means to detachably and movably mount said furnace on the machine for movement in the plane of the movement

of the die members as a part of the operating cycle of the machine.

19. An automatically operating die casting machine including a pair of die members, means to periodically open and close said die members, one of said members having a sprue opening extending therethrough at an angle to the parting line of the members, a melting pot furnace, and means to move the furnace in a direction angularly to the parting line of said die members and in timed relation to the opening and closing operations, to permit communication between the pot and die cavity through said sprue opening for a portion of the interval during which the die members are closed.

20. The structure of claim 19 and means to exert pressure on the metal in the pot and a control device therefor, automatically operable to permit said means to act during the period of communication of the pot with the cavity.

21. The structure of claim 19 and means to exert pressure on the metal in the pot and a control device therefor, automatically operable to permit said means to act during the period of communication of the pot with the cavity, a core associated with one of said die members and mechanism for moving the core into the cavity after the die is closed and prior to the casting operation and to withdraw said core after completion of the casting operation and prior to the separation of the die members.

22. The structure of claim 19 and means to exert pressure on the metal in the pot and a control device therefor, automatically operable to permit said means to act during the period of communication of the pot with the cavity, a core associated with one of said die members, mechanism for moving the core into the cavity after the die is closed and prior to the casting operation and to withdraw said core after completion of the casting operation and prior to the separation of the die members, an ejector associated with the other of said die members and movable relative thereto after separation of the dies.

23. The structure of claim 19 and means to exert pressure on the metal in the pot and a control device therefor, automatically operable to permit said means to act during the period of communication of the pot with the cavity, and means associated with one of the die members to eject the completed casting when the die members are opened.

24. An automatically operated die casting machine including a stationary die member, a relatively movable die member, a melting pot furnace movable relative to and in the same direction of movement of said movable die member, a main drive shaft, cam elements carried thereby and associated respectively with the furnace and movable die member, said cam elements being arranged to

close and open the die members and to move the furnace and place the melting pot into and out of communication with the die cavity when the die members are closed.

25. The structure of claim 24, and means governed by drive shaft rotation to discharge metal from the melting pot when communication is established with the die cavity.

26. The structure of claim 24, and means governed by drive shaft rotation to discharge metal from the melting pot when communication is established with the die cavity, an ejector associated with the stationary die member and actuated by a cam element on the drive shaft to push a completed casting from the die member.

27. The structure of claim 24, and means governed by drive shaft rotation to discharge metal from the melting pot when communication is established with the die cavity, an ejector associated with the stationary die member and actuated by a cam element on the drive shaft to push a completed casting from the die member, and a core having an operable connection with a cam element on said driven shaft so as to be projected into the die cavity prior to the casting operation and to be withdrawn therefrom after the casting operation.

28. The structure of claim 24, and means governed by drive shaft rotation to discharge metal from the melting pot when communication is established with the die cavity, and a core having an operable connection with a cam element on said drive shaft so as to be projected into the die cavity prior to the casting operation and to be withdrawn therefrom after the casting operation.

29. The structure of claim 24, a clutch controlling the transmission of power to rotate said shaft and means operated by the shaft to disengage the clutch after the shaft has made a complete rotation.

30. An automatically operated die casting machine, including a stationary die member, a cover die member movable to and from said stationary member, and having a sprue opening leading to the die cavity at an angle to the parting line of the die members, a melting pot having a discharge nozzle and movable relative to said die members to bring the nozzle into communication with the sprue opening when the die members are closed, and means to automatically move said cover die member and melting pot in predetermined relation and thru continuously repeating cycles.

31. The structure set forth in claim 30, said means comprising a drive shaft, rotatable cam elements carried thereby, and connecting rods having portions engageable with the cam elements and cover die member and melting pot respectively.

32. An automatically operated die casting machine including a drive shaft, a series of

cam elements carried by the shaft, a fixed die member, a movable cover die member, means whereby one of said cam elements reciprocates said cover die to closed and opened position, a melting pot, and means associated with another of said cam elements to bring said melting pot into communication with the die cavity for a predetermined period when the die members are closed, ejector pins associated with the fixed die member and operably connected with a cam element on said shaft for ejecting the casting after the die members are opened.

33. An automatically operated die casting machine including a fixed die member, a relatively movable die member, cores insertable and removable from the die cavity, a melting pot furnace movable relative to said die members to bring the pot into communication with the die cavity, means to force metal from the pot into the die cavity, ejector pins associated with the fixed die member, a drive shaft and cam elements associated with the shaft and respectively with certain of the elements before mentioned and adapted upon a complete rotation of the shaft to bring such elements into action according to a predetermined sequence.

34. The structure of claim 35, and a clutch governing transmission of driving power to said shaft, and means operated from the shaft to disengage the clutch upon a complete rotation of the shaft.

35. In an automatically operated machine of the character described, wherein a series of parts are operated in timed relation thruout successive cycles, a rotary shaft, a series of cam elements rotatable therewith to control the movement of said parts in predetermined sequence, a clutch controlling the transmission of power to rotate said shaft, manually operated means to engage and disengage said clutch, and means associated with the shaft to automatically disengage the clutch after a given cycle of operations have been completed, said last mentioned means including a crank mounted on the shaft, a reciprocatory link connected with the crank and adapted at one limit of its movement to engage with a clutch release element.

36. In a die casting machine, a pair of separable die members, one of which is provided with a sprue opening extending angularly to the parting line of the die members, a melting pot including a nozzle to discharge a molten charge into said die through said sprue opening, at least one of said parts being movable, knee members upon which said melting pot is mounted and means to adjust the position of said knee members and melting pot to accurately position the nozzle relative to the sprue opening.

37. In a die casting machine, a die member, a melting pot having associated therewith a nozzle to charge the die, means to move the

melting pot to a position wherein the nozzle is in charging position, said means including a rocking member, a link connecting said rock member and melting pot, the connection between said rocking member and link including resilient means whereby to compensate for variation in the relation between the nozzle and the die.

38. The invention defined by claim 37, said resilient means being constituted by a rubber block.

39. A die casting machine including a frame, a die section stationarily mounted on the frame, a movable die section, a unit movable relative to and in the same plane of movement of said die section and including a furnace and a melting pot, and means for automatically moving the movable die section and said unit in predetermined timed relation.

40. A die casting machine including a frame, a die section stationarily mounted on the frame, a movable die section, actuating means for said movable die section to close and open the die, a unit movable relative to said die section and in a plane angular to the meeting faces of the die sections and including a furnace and a melting pot, actuating means for moving the unit to and fro in timed relation with the movement of said movable die section to automatically place the melting pot in communication with the die cavity when the die sections are closed.

41. The structure of claim 40 and automatically actuated means to force molten material from the pot into the closed die cavity.

42. A die casting machine including a frame, a die section stationarily mounted on the frame, a movable die section, actuating means for said movable die section to close and open the die, a platform slideable on said frame, a melting pot and furnace carried by said platform, and actuating means to slide the platform in predetermined relation to the movement of said movable die section to bring the discharge passage of the pot into combination with the closed die cavity through a sprue opening extending through one of the sections at an angle to the meeting faces of the sections.

43. A die casting machine including a stationary die member, a cover die member movable relative to the stationary die member and having a sprue opening extending therethrough at an angle to the parting surfaces of the die, a furnace and melting pot unit movable relative to the cover die and in the plane of movement of the cover die to bring its nozzle into communication with the sprue opening.

In testimony whereof I affix my signature.
MARC STERN.
